Application March 2, 1950, Serial No. 147,207

4 Claims. (Cl. 153—80)

1

When pipes are hydraulically tested in the customary way their ends are placed in heads which snugly surround them and are provided with gaskets to form a seal for the water admitted to the interior of the pipe; in consequence the pipe extending between the heads is expanded up to approximately 2% and cold worked, but as the ends are clamped in the heads they do not receive this expansion and working and after the test are of less diameter than the main body of the pipe. It results that when the pipes are cut in the field the diameter between the ends does not coincide with that of the end of another pipe of presumably similar size while the ends themselves are untested and devoid of the cold working to which the bodies of the pipes have been subjected.

It is therefore an object of this invention to provide apparatus adapted to test and cold work the ends of a pipe and to likewise expand them the same amount that the remainder of the pipe will be expanded when subsequently subjected to the usual hydraulic expansion and test so that the pipe will then be of the same diameter and have substantially the same physical characteristics from end to end.

A further object is to provide apparatus through the medium of which one end of a pipe can be expanded substantially the same amount as the body of the pipe will be subsequently expanded through subjection to hydraulic test and the other end can be expanded to a much greater degree to provide the bell component of a bell and spigot joint with another pipe.

Further objects are to provide an apparatus of the character to which reference has been made comprising novel means for supporting and clamping the pipe in position for expansion at its ends irrespective of its wall thickness whereby a single apparatus is adapted to receive and expand pipe of various wall thicknesses and of various lengths, and to provide in such apparatus mechanisms by which the expansion of the ends is directly effected and which may be adapted for use with pipes of different diameters by simple removal and replacement of but few parts with those of other size each time that pipes of different nominal size are to be operated upon.

A still further object is the provision of apparatus embodying the foregoing characteristics which is largely automatic in character and requires but a single operative to cause it to receive a pipe, position it for expansion of its ends, effect the expansion of the latter and then discharge it for further processing such as subjection to an hydraulic test.

Other objects, advantages and novel features of design, construction and arrangement com-

2

prehended by the invention are hereafter more particularly pointed out or will be apparent to those skilled in the art from the following description of one form of apparatus constructed in accordance therewith and illustrated in the accompanying drawings in which:

Fig. 1 is a diagrammatic top plan view of the apparatus also showing portions of a conveying mechanism desirably positioned adjacent one of its ends for receiving each pipe after it is expanded;

Fig. 2, on a larger scale, is a fragmentary front elevation of the apparatus, a pipe resting on the rolls of the roll carriages being indicated in broken lines in this figure;

Fig. 3, on a like scale, is a transverse section substantially on line 3—3 in Fig. 2;

Fig. 4 is an enlarged view of a portion of the apparatus on the same sectional plane as Fig. 3;

Fig. 5, on a much larger scale, is a top plan view of one of the roll and clamp carriages;

Fig. 6 is a side elevation thereof;

Fig. 7 is an end elevation looking to the right in Fig. 6 with certain of the parts broken away or omitted for the sake of clearness;

Fig. 8 is an end view of one of the pipe clamps and associated parts;

Fig. 9 is a top plan view thereof;

Fig. 10 is a vertical section showing the pipe clamping mechanism on the line 10—10 in Fig. 9;

Fig. 11 is a fragmentary view corresponding to a portion of Fig. 8 showing the clamping fingers in open position;

Fig. 11-a is a diagrammatic view illustrating different positions assumed by the free ends of said fingers when clamping various sizes of pipe;

Fig. 12 is a top plan view of one of the expander head buggies;

Fig. 13 is a side elevation thereof;

Fig. 14 is a view, partially in longitudinal section and partially in side elevation, of one of the expander heads;

Fig. 15 is a front end view thereof;

Fig. 16 is a central section of the tool retaining cap used when operating on pipe of large size, and

Fig. 17 is a fragmentary view generally corresponding to Fig. 14 but showing one of the expander heads arranged for expanding pipe of size larger than the head shown in Fig. 14.

General organization and operation

The pipes to be expanded in the apparatus are conveniently consecutively delivered to it on the conveyor C on which they move in the direction of the arrow in Fig. 1, each pipe having been previously sized, straightened and its ends cut off

and chamfered if desired. When the leading end of the first pipe reaches a point a little in advance of transverse alignment with the so called stationary expander head hereinafter described, it encounters a flag switch or other device (not shown) effective to cause the kickouts K to lift it from the conveyor rolls and move it sideways onto the skid table S , the kickout shaft l being actuated from a suitable motor and gear or crank unit M connected therewith. A manually operated switch may be provided if desired to enable the operator to actuate the kickouts should the flag switch not function properly. The skids of the skid table are inclined downwardly and forwardly so that the pipe after transfer to them will roll down on the skids until arrested by the arms of the escapement E (shown more in detail in Fig. 4), the escapement shaft 2 being appropriately driven from a motor and gear or crank unit M' which allows one pipe at a time to pass to adjustable skids S' from which it moves to still other skids and finally to the rolls 3 of the roll and clamp carriages R of which two are desirably provided, these carriages being movable on tracks T and also supporting the last mentioned skids. T

The rolls 3 having been previously set at the proper height the pipe is now in axial alignment with the axes of the expander heads H, H' , the former of which is mounted on an expander head buggy B likewise movable on tracks T , and this buggy is next moved along the tracks to the right in Fig. 1 until its head contacts and its expander plug enters the trailing end of the pipe. Further movement of the buggy then pushes the pipe against the expander head H' which is longitudinally movable relatively to the fixed base 4 on which it is supported and, being now in advanced position, i. e. as far as possible to the left in Fig. 1, is pushed back to the right by the pipe to a small extent depending on the momentum and weight of the pipe its expander plug meanwhile telescoping in the adjacent end of the pipe. During these operations the exhaust valves of hydraulic rams A which are respectively associated with the heads are open so that both heads can attain their respectively retracted positions. Movement of the pipe to the right in Fig. 1 being thus ultimately arrested the operator, through suitable actuating mechanism, causes a pawl to drop from each side of the movable buggy B into the teeth of a rack 5 adjacent and paralleling each track rail thus locking buggy B against retrograde movement, that is movement to the left, save for the limited amount which may be required to firmly seat the pawls in the racks. The pipe clamps carried by carriages R are next raised and caused to engage the pipe at spaced intervals to thereby prevent it from subsequent buckling during the actual expanding of its ends and fluid is admitted to the ram cylinders, the initial result of which is to move the buggy B backward until the pawls are firmly seated in the racks after which further movement of the rams actuates the expander heads to expand the ends of the pipe into which their respective expander plugs are telescoped.

The expansion being effected, the plug of head H' is collapsed sufficiently to free it from the pipe end, the pawls are raised, the pipe clamps opened, and buggy B then traversed rearwardly, drawing the pipe along the supporting rolls by means of its still expanded plug until the leading end of the pipe fully clears the plug of head H' and a suitably disposed toggle switch 6 which operates to collapse the plug of head H and so allow the

buggy and head to move away from the pipe. Thereupon another toggle switch 7 carried by the buggy is actuated as it clears the pipe and operates to cause the kickouts K' to lift the pipe from the rolls on carriages R, R and discharge it onto conveyor C' which then translates it still farther to the right until it is aligned with a transfer table X (fragmentarily shown in Fig. 1) which transfers it to another conveyor Y conveniently in alignment with conveyor C which carries it to the hydraulic testing machine or other apparatus in which it is to be subjected to further treatment.

A single cycle of the machine having thus been completed, during which both ends of a pipe P have been simultaneously expanded and cold worked, the apparatus is now in condition for repetition of the cycle on the next succeeding pipe, so that more specific reference may now properly be had to the various instrumentalities and their details of construction and operation through which are accomplished the various steps incident to each such cycle.

Escapement mechanism

As the pipes roll down the inclined skids S from kickout mechanism K , which requires no specific description being of usual or any other construction suitable to lift the pipes consecutively from conveyor C and discharge them onto said skids, the leading pipe encounters arms 10 of the escapement (Fig. 4), these arms being mounted on the squared longitudinally extending shaft 2 which as above mentioned is actuated from motor M' . Each escapement arm at its normally uppermost extremity is provided with a finger 11 and at its opposite end with an abutment 12 , and as shaft 2 is turned in a counterclockwise direction the pipe will roll down the body of the arm until it hits the finger while abutment 12 will rise into the path of the next succeeding pipe and hold it back on skids S . Adjacent the escapement mechanism are a series of pedestals 13 each of which carries a downwardly inclined skid S' upon which the escapement arms place the pipe, each skid being adjustably secured to its pedestal by pins 15 which may be passed through any of a series of holes 16 in the pedestal and skid so as to change the elevation and inclination of the latter at will to adapt it to receive pipe of different diameters from the escapement. From skids S' the pipe then passes to other skids hereinafter described which are carried by the roll and clamp carriages.

Roll and clamp carriages

Each of these carriages, of which two are preferably provided, comprises a truck-like frame 20 mounted on four wheels 21 which rest on tracks T and so enable the carriages to be moved longitudinally thereof as required. As best shown in Figs. 5, 6 and 7 the frame is cut out centrally to provide an opening 22 for reception of an inner frame 23 which is pivoted at one end on a pivot 24 so its other and free end can swing vertically; on this inner frame a roll 3 is suitably journaled for revolution about a horizontal axis extending transversely of the carriage and is concaved on its surface so as to form a seat for the pipe. A T-headed screw 26 normally is threaded through a lug 27 on the main frame 20 and underlies the free end of the inner frame whereby the latter can be raised or lowered by adjusting the screw and so correspondingly raise or lower roll 3 so it will support pipes of different diameters in co-

axial alignment with the expander heads; it will be evident that the roll will consequently be set at a higher point for a pipe of small diameter than for a larger one. To afford an even wider range of adjustment in this regard, a pocket 30 is formed in the main frame and the free end of the inner frame provided with a tongue 31 extending thereinto, the pocket being adapted to hold a generally rectangular filler block 32 (Fig. 7) having a threaded bore into which the T-headed screw 26 can be screwed when it is desired to raise the roll to a point higher than that attainable by the screw when threaded in lug 27.

Mention has been made of skids which receive the pipe from skids S' and transfer it to the rolls 3. As best shown in Figs. 5 and 7 each of these skids 35 which are supported by the roll and clamp carriages is pivoted at 36 in pad or ear 37 on the carriage inner frame and extends transversely outward therefrom toward skids S', and to facilitate angular adjustment of the skid a bracket 38 is secured to a pad or bracket 39 on the main frame and receives the lower end of a threaded clevis 40 which in turn receives and is pivoted to the outer end of the skid; thus by adjustment of the clevis the inclination of the skid can be appropriately adjusted in accordance with the size of the pipe to be received on it. Preferably to increase the range of this adjustment bracket 38 is fixed to its pad 39 in such way 30 it can be raised or lowered with respect thereto.

Pipe clamps

Each of the roll and clamp carriages R also supports a pipe clamp, hydraulically or pneumatically actuated and so constructed it is effective to grip above its axis any size pipe within the limits of the apparatus as a whole and force the pipe snugly down against the subjacent roll 3 so that the pipe is then prevented from bending or otherwise getting out of line during the expanding of its ends.

More specifically each carriage frame 20 is provided at one end with an integral depending portion 45 which extends into a channel 46 (Fig. 3) between tracks T and in which an hydraulic or pneumatic cylinder 47 is pivotally mounted on pivots 48; a piston rod 49 extends generally upward from the piston in this cylinder and is pivoted to a head 50, and the depending portion 45 of the carriage frame is channeled out to form ways 51 in which the head is slidable vertically, the frame also being provided with openings for the passage of horizontally extending rods 52 which form bearings for certain of the links associated with the clamp fingers 55 one of which is disposed on each side of the axis of the pipe when resting on the rolls and which are shaped at their free ends approximately as shown in Figs. 8 and 10. The fingers about midway of their lengths are connected by a solid substantially U-shaped tie 56 the extremities of which are pivoted to them and which at its center is provided with a pin 57 carrying rollers 58 on its extremities which also ride in ways 51; in lieu of rollers, blocks adapted to slide in the ways may be utilized on the end of this pin. The lower extremities of the fingers are pivoted on pivots 59 to links 60 which at their other extremities are pivoted on rods 52 and consequently during the operation of the clamp move around the axes of these rods as fixed centers. The lower ends of the fingers are also pivotally connected through links 61 with head 50 with the result that when the head is reciprocated in its ways the upper ends of the

5 fingers are opened out or moved together in such manner that whatever be the diameter of the pipe or rolls 3 the free ends of the fingers when closed upon it always engage it slightly above the horizontal plane of its axis coincident with the axis of the expander plugs and thus tend to force the pipe down against the subjacent rolls.

6 This action of the fingers will be readily apparent from an inspection of Figs. 8, 11 and 11a. In Fig. 8 they are shown closed on a pipe P of relatively small diameter and it will be noted that they engage it, as stated, somewhat above its center; in Fig. 11 they are shown open to their full extent as a result of maximum retraction of piston rod 49 in cylinder 47 and thus as they would appear preparatory to or just after a pipe has been positioned on the rolls and prior to their being closed in upon by upward projection of the piston and piston rod upon admission of fluid to the lower end of cylinder 47, while in Fig. 11a there is diagrammatically shown respectively the positions of the fingers when closed on three pipes P^a, P^b, P^c of different diameters each supported in coaxial alignment with the expander heads. In each case the fingers contact the pipe above its axis, a result which is always true irrespective of the exact diameter of the pipe when so supported, save where it exceeds the maximum and minimum sizes which the clamp is designed to accommodate.

Expander head mountings

The movable buggy on which the expander head H is mounted and as best shown in Figs. 12 and 13 comprises a frame 70 carried on wheels 71 movable on tracks T and at its rear end supporting a motor 72 adapted through suitable gearing, generally designated 73, to drive the adjacent wheels 71 so that by operation of the motor in one direction or the other the buggy may be propelled along the tracks. At each side of the frame is a hold down 74 comprising a depending portion and an inwardly directed lip extending under the adjacent track rail head thus insuring the buggy constantly remaining on the tracks. The frame supports an hydraulic thruster 75 of appropriate character for raising or lowering the pawls 76 suitably mounted adjacent each side of the frame for cooperation with rack 5 of which mention has already been made.

50 A motor and pump unit 77 is mounted on the frame for furnishing fluid under pressure to an hydraulic ram cylinder 78 which through piston rod 79 supplies the power for actuating the expander plug of the expander head H hereinafter more fully described.

In a manner generally similar to the roll and clamp carriages R, R, frame 70 is cut out to receive an inner frame 23' pivoted at one end and supporting a roll 3', the frame being vertically adjustable through the medium of mechanism like that already described in connection with frame 23 to enable roll 3' to be appropriately positioned for reception of pipe of different sizes. 60 Near its forward extremity the frame is provided with a vertically extending slot for the reception of one of the kickouts K' which is slidable therein and actuated from an hydraulic power cylinder and piston (not shown), the kickout when raised being effective to lift the pipe from the roll on which it is supported while being expanded and eject it to conveyor C' or onto suitable skids (not shown) leading thereto. To this end the upper edge of the kickout is appropriately inclined and similar kickouts arranged for simultaneous actu-

ation are associated with each of the carriages R, R, and with buggy B and base 4 on which heads H, H' respectively are mounted.

The last mentioned head is, as previously stated, mounted on a fixed base 4 and is longitudinally slidable thereon the base of course being provided with suitable ways 80 for this purpose; the head H, is also slidable on its buggy B.

In a manner generally similar to that hitherto described, the base 4 supporting head H' is cut out to receive an inner frame 23" pivoted at its outermost end for vertical movement and supporting a roll 3" (Fig. 2), the frame being arranged for vertical adjustment at its free end similarly to the other inner frames so that the roll may be properly positioned to support a pipe of given diameter at the level of the expander heads.

Inner frame 23" also supports the toggle switch 6 and the corresponding inner frame on buggy B 20 the other toggle switch 7 which are respectively actuated at the proper points in the cycle as hitherto described.

Expander heads

These heads are of generally similar construction so that with certain exceptions hereinafter noted a description of one of them, for example H', more particularly illustrated in Figs. 14 and 15 will suffice for head H carried by buggy B.

More particularly each head comprises a generally hollow cylindrical housing 90 slideable on ways 80 and behind the head is disposed the ram cylinder 78' which through piston rod 79' furnishes the power to effect the expansion, this cylinder being appropriately connected by piping with the pump of a motor pump unit (not shown) similar to unit 77 connected with cylinder 78. Suitable valves are of course supplied for admitting to and exhausting fluid from the respective cylinders.

Piston rod 79' is connected with a plunger 91 extending axially through the housing, while surrounding this plunger is a cylindrical plunger 92, bushings 93 of suitable bearing material being respectively interposed between plungers 91 and 92 and between the latter and the housing. The rear end of the cylindrical plunger is bored out and threaded to receive a ring 94 the end of which normally projects beyond it and forms 50 a stop for a flange 95 on the rear end of plunger 91 while another ring 96 is similarly threaded into the rear end of the housing in alignment with a peripheral flange on the rear end of cylindrical plunger 92 provided with holes for the passage of bolts 97 which when in position as shown in Fig. 14 operatively unite the cylindrical plunger and ring 96. The rear end of ring 94 is likewise provided with holes 98 internally for the reception of the same or similar bolts when passed through corresponding unthreaded holes in the flange 95 so as to operatively unite it with the ring when desired.

Near its forward end, that is the end remote from connection with rod 79', the plunger 91 is inwardly tapered and of polygonal cross-section as at 99, and supports a plurality of segmental expanding tools 100 which are held in place by a cap 101 and retaining bolt 102 threaded into the extremity of the plunger and also by a face plate 103 bolted to the proximate end of the cylindrical plunger and provided with an annular flange 104 overlying the adjacent ends of the tools, the cap and flange being of sufficient internal diameter to permit the segments to move.

outwardly for an adequate distance during the expanding operation.

The segmental tools as a whole constitute the expander plug 105 and are in number similar to the polygonal faces of portion 99 of plunger 91, the segments of course being grouped about the latter. The outer surface of each segment is arcuate in planes transverse to the axis of the head and parallel to that axis for a suitable distance from the face plate 103 adjacent which it has a shoulder 100a engageable with the pipe end. Forwardly of this point it is inclined inwardly to facilitate entry of the plug into the pipe, each segment also having a finger-like portion adapted to extend into the cap 101, while the inner surface of the segment is inclined in correspondence to the faces of the polygonal section of the plunger so as to seat snugly thereon but desirably parallel to the axis of the head in the said finger-like portion. It results that when the plunger is retracted to the right in Fig. 14 the segments of the tool collapse inwardly while when the plunger is advanced after engagement of the tool in the pipe end the segments are forced outwardly to expand the pipe.

The expander plug just described is typical of those used for expanding pipe of smaller sizes while for those of larger diameter other plugs comprising a plurality of generally similar but larger tool segments 110, Fig. 17, are provided, these segments then being operatively grouped about the end of cylindrical plunger 92 which end is likewise of polygonal cross section, a removable face plate 111 having an annular flange 112 overlying the inner ends of the tool segments when so grouped and being bolted or otherwise removably secured to the face of the housing 90, the flange 112 providing appropriate clearance between the tools and itself when the segments are in position.

It will be understood that when a smaller plug 105 is to be used the tools 110 are removed but when it is desired to operate on larger sizes of pipe the smaller tools together with cap 101 and face plate 103 are taken off and in lieu of the latter a flanged cap 113 (Fig. 16) suitable for retaining the finger-like ends of tools 110 in place is substituted therefor and secured in position.

It will now be apparent that when a pipe P of size suitable for expansion by expander plug 105 is telescoped thereover and the piston then actuated through admission of fluid to ram cylinder 78' so as to force plunger 91 to the left in Fig. 14, the segmental expanding tools 100 are forced radially outward inside the pipe to effect its expansion, ring 94 being adjusted to arrest the movement of the plunger when the proper degree of expansion has been attained. However, when a pipe of larger size is to be expanded through the use of the expander tools 110, face plate 103, tools 100 and associated parts are removed as hitherto stated and cap 113 substituted for the face plate. Bolts 97 are then removed and inserted through the holes in flange 95 and the latter bolted to ring 94 so that plunger 91, ring 94 and cylindrical plunger 92 will form an operative unit with ring 96 acting as a stop for this unit to arrest its movement under the influence of piston 79' when the proper degree of expansion has been attained.

The expanding tools illustrated are shown with their edges lying in radial planes which is the construction preferably employed when the apparatus is used for only slightly expanding pipe

ends so as to compensate for subsequent expansion of the body between them under hydraulic test and also to effect cold working of the ends, but when a pipe end is to be expanded to a much greater degree, as for example when forming the bell of a bell and spigot joint thereon, the edges of the expanding tools are desirably made in a spiral or at an angle to the longitudinal axis of the head to prevent marking the inside of the pipe as the expanding plug is forced into its end as will be readily understood by those familiar with this art, the precise contour of the edges of the tools being a matter of choice and largely dictated by the work they are designed to perform.

The foregoing description of the expander heads applies equally to either of them and it has been mentioned that both heads are longitudinally slidable on ways, and means are associated with these heads to cushion the shock when the end of the pipe encounters the expander plug as it is moved thereagainst by the forward motion of the buggy B, thereby avoiding risk of injury to the ends of the pipe. The housing 90 of head H' thus comprises a depending lug 120 receiving a plug 121 bearing on one end of a coil spring 122, the other end of which bears on a generally similar plug 124 received in stationary frame 4, the two plugs being desirably connected by a rod 125 and a similar construction is also provided on head H. The aforesaid shock is thus cushioned against the springs and any chance of injury to the pipe ends obviated.

Control

The apparatus may readily be controlled by a single operative stationed in a pulpit positioned at some point from which he can readily observe the progress of the pipe through the apparatus and the action of the latter thereon so he may properly operate valves and other instrumentalities for effecting the various steps incident to the cycle. These valves and other instrumentalities may be of any type appropriate for the performance of their respective functions and so require neither illustration nor particular description since they are well understood in the art and readily available for association with a machine of this character. Moreover if desired some of them at least may be automatic in operation as distinguished from manually actuated, but in either case it is apparent in addition to the operations effected by switches 6, 7 it is necessary for the full performance of the cycle that the kickouts K raise the pipes consecutively from conveyor C; that the escapement shaft 2 be appropriately turned to allow the pipes to pass one at a time to the skids which lead them to rolls 3, which of course have been adjusted to the proper height for the size of pipe to be expanded; that buggy B be then moved toward head H', while the exhaust valves in cylinder 78 are opened; that thruster 75 be actuated to drop the pawls into the racks alongside the tracks; that clamps 55 be closed in against the pipe; that piston rods 79, 79' be moved so as to expand the expander plugs; then, after the expansion is effected, that the piston associated with the head H' be retracted to collapse its plug; the clamps released and finally after the plug of head H is collapsed and cleared from the pipe and the buggy moved out of the way through automatic operation of switches 6, 7, that kickouts K' be raised to discharge the expanded pipe upon con-

veyor C' and then retracted to their normal position.

Reference has been made to expanding pipes of different wall thicknesses and of different diameters and it will be understood that the apparatus I have devised is within limits substantially universal in these respects. Thus a given set of tools for example, the tools 100 with their associated cap 101 and face plate 103, may be suitable for expanding pipe of 6" nominal size, i. e. pipe of 6 $\frac{5}{8}$ " O. D. but of any wall thickness in that size, since the control of the effective maximum diameter of the expander plug which is afforded by the adjusting ring 94 enables the ends of the pipe to be expanded to any desired degree without regard to its wall thickness.

Likewise the tools 110 may be adapted for expanding pipe of say 16" nominal size and O. D. regardless of wall thickness, the adjusting ring 96 providing accurate control of the extent of expansion whatever be the ultimate O. D. or wall thickness.

Furthermore on simply removing the bolt 102, cap 101, tools 100 and face plate 103 are replaceable by corresponding parts of different size for accommodating pipes of other than 6" nominal size, for example up to about 14", while an assortment of larger tools 110 with corresponding caps 113 and face plates 111 may also be provided for expanding pipes of each nominal size from 14" to 22" and the appropriate set selected and installed in the apparatus on simple manipulation of their retaining bolts.

Furthermore as the degree of expansion of the pipe ends which may be effected by this apparatus is limited only by the expansive capacity without rupture of the pipe wall it will be evident that pipe which may be expanded at its ends sufficiently to form the bell element of a bell and spigot joint may be suitably belled at one end with the aid of the apparatus. Preferably to form a bell, the expander plug on the stationary head before the pipe is brought against it is adjusted through control of cylinder 78' to a size corresponding to the desired ID of the bell to be produced. The pipe, secured to the expander plug of the movable buggy in the usual way is then brought against the stationary plug by movement of the buggy and with the pipe clamps adjusted to allow its limited axial movement the expander plug of the buggy is projected forwardly by operation of cylinder 78 to force the opposite pipe end over the stationary plug and thereby expand it to a bell, after which the belled pipe is discharged in the usual way.

While I have herein described with considerable particularity one embodiment of the invention it will be understood I do not desire or intend to be thereby limited or confined thereto in any way as changes and modifications in the form, structure, relationship and arrangement of the several parts and instrumentalities employed will readily occur to those skilled in the art and may be made if desired without departing from the spirit and scope of the invention as defined in the appended claims.

Having thus described my invention, I claim and desire to protect by Letters Patent of the United States:

1. In apparatus of the class described, a pipe expander head comprising a housing, an outer plunger axially slidable therein having a tapered surface at one of its ends, an inner plunger axially slidable in the first plunger and having a tapered surface at its corresponding end, means for se-

lectively retaining a plurality of segmental pipe expanding tools in engagement with the tapered surface of either plunger, means for sliding the inner plunger axially in the outer plunger, and means for releasably securing the plungers together whereby to axially slide the inner and outer plungers unitarily with respect to the housing when the inner plunger is actuated by its said sliding means.

2. In apparatus of the class described, a pipe expander head comprising a housing, an outer plunger axially slideable therein having a tapered surface at one of its ends, an inner plunger axially slideable in the first plunger and having a tapered surface at its corresponding end, means for selectively retaining a plurality of segmental pipe expanding tools in engagement with the tapered surface of either plunger, means for sliding the inner plunger axially in the outer plunger, axially adjustable means for releasably securing the outer plunger to the head, and axially adjustable means carried by said outer plunger for limiting movement of the inner plunger in one direction.

3. In apparatus of the class described, a pipe expander head comprising a housing, an outer plunger axially slideable therein having a tapered surface at one of its ends, an inner plunger axially slideable in the first plunger and having a tapered surface at its corresponding end, means for selectively retaining a plurality of segmental pipe expanding tools in engagement with the tapered surface of either plunger, means for sliding the inner plunger axially in the outer plunger, axially adjustable means for releasably securing the outer plunger to the head, and axially adjustable means carried by said outer plunger for limiting movement of the inner plunger in one direction said last mentioned means being adapted for securement to the inner plunger when the outer plunger is released from the head to thereby slide said outer plunger unitarily with the inner

plunger when the latter is actuated by its said sliding means.

4. In apparatus of the class described, an expander plug comprising a plurality of coaxial substantially segmental expander tools each having opposed inner and outer tapered surfaces, the inner surface being substantially plain and the outer surface corresponding to a segment of a surface generated by movement about the plug axis of a line disposed at an acute angle to said axis, and a movable plunger axially aligned with and extending within said plug having plane surfaces disposed angularly to the plug axis respectively corresponding to and engageable with the inner surfaces of the tools for forcing said tools radially outward from said axis, the plug including a removable tool retaining cap carried by the plunger surrounding the end portions of the tools adjacent one end of the plug and a tool retaining ring surrounding the opposite ends of the tools.

LUTHER S. RESSER.
